UNITED STATES PATENT OFFICE.

EMIL TYDEN, OF CHICAGO, ILLINOIS.

SEAL.

SPECIFICATION forming part of Letters Patent No. 614,634, dated November 22, 1898.

Application filed February 5, 1898. Serial No. 669,172. (No model.)

To all whom it may concern:

Be it known that I, EMIL TYDEN, a citizen of the United States, residing at Chicago, county of Cook, and State of Illinois, have invented certain new and useful Improvements in Self-Locking Seals, which are fully set forth in the following specification, reference being had to the accompanying drawings, forming a part thereof.

10 In the drawings, Figure 1 is an elevation showing a hasp secured by a bolt which is retained by my improved self-locking seal. Fig. 2 is a plan of my seal having the cap removed to show the interior structure, the position of the parts being that occupied before locking. Fig. 3 is a similar view showing the position of the parts after locking. Fig. 4 is a section at the line 4 4 on Fig. 2. Fig. 5 is an end or top view of the case. Fig. 20 6 is a plan of the blank from which the tripper-sheath is formed by folding. Fig. 7 is a plan of the tripper. Fig. 8 is an elevation of a bolt suitable for use in the seal illustrated in the foregoing figures. Fig. 9 is an elevation of a modified form of seal applied to a suitably-modified bolt. Fig. 10 is a sectional plan or edge view of the same, section being made at the line 10 10 on Fig. 9.

The present invention involves fundamentally the locking principle which is shown in my United States Patent No. 594,580, dated November 30, 1897; but this principle is herein embodied in a device adapted to be secured to a locking-bolt or other fastening by means which does not require the end of the tripper which is to be engaged by the catch to be first passed through the bolt or other device which is to be locked, and therefore permits the tripper to be by construction lodged in the seal body or case and requiring only movement therein to cause it to become engaged with the catch.

In the form of the device shown in Figs. 1 to 8, inclusive, the tripper, which is by construction lodged in the seal body or case, has an end which protrudes therefrom alongside of a protruding arm of the case, these two parts having apertures which may register with each other and permit the head of the bolt to be inserted through them, one of the parts having a slot running from the aperture and the bolt having a neck which is

drawn into such slot by the locking movement of the tripper, thus preventing the escape of the head.

In the form shown in Figs. 9 and 10 the tripper is formed in one piece with the protruding arm of the case, constituting an exterior loop large enough at unlocked position to be slipped over the head of the bolt, but which is reduced by the movement of the tripper to locked position, so that it only encompasses the neck and will not permit the escape of the head.

These two forms sufficiently illustrate the scope of the idea involved and will suggest to any one familiar with the art other applications of the same idea within the scope of this part of my invention.

In both forms illustrated the arm of the case, alongside of which the tripper extends, is preferably formed of a separate piece of metal from the case proper—that is to say, from the part which incloses and conceals the catch. This part of the case, which includes the extended arm, I term the "tripper-sheath," because it serves as the guide and seat for the tripper in its movement from unlocked to locked position. A is this tripper-sheath, which is most conveniently made of a piece of sheet metal (shown in a blank at Fig. 6) adapted to be folded at a, bringing the two similarly-shaped leaves or wings A' and A² face to face and with the apertures A¹⁰ A²⁰ coinciding. The metal is struck out of the fold a to form a lug or engaging offset a', which serves to fix the position of the sheath in the case, which is approximately spherical in form and made of two pieces B' and B², secured together by engaging flanges at a diametric plane in a manner familiar to metal-workers, and which will be understood from the drawings without further explanation. The part B' of the case has at diametrically opposite points broad notches B¹⁰ B¹¹, in which the tripped sheath is lodged, the lug or offset a' lodging within the case and serving to stop the sheath against longitudinal movement therein, lateral movement being prevented by the fitting of the sheath in the notches. An aperture a¹¹ is left through the fold a when the offset a' is struck out, the purpose of which will be hereinafter explained. C is the tripper. It is lodged between the

leaves A' and A² of the sheath and extends out between them through the notch B¹⁰. In this seal I have shown four catches D D D D, each being a coiled ring of spring-wire whose 5 ends lap in the normal condition of the coil, but which is adapted to be spread open to permit the ends to be entered through apertures a¹⁰ and a²⁰ in the two leaves A' A² of the sheath. The tripper Chas a tooth c, which 10 enters the slot a¹¹ of the sheath. It has also an elongated aperture or slot C' in position to register with the apertures a¹⁰ and a²⁰ when the tripper is at proper longitudinal position, but out of registration therewith at unlocked 15 position, as seen at Fig. 2, so that at that position the catches D D spread open and, having their ends entered through the slots a¹⁰ and a²⁰, are held open by the tripper inserted between the leaves of the sheath. The parts 20 being assembled in this position, the cap-piece B² of the case being put in position and the two parts of the case clenched together, the aperture C² of the tripper, in the form shown in Figs. 1 to 8, registers with the apertures A¹⁰ and A²⁰ of the sheath, and the tooth 25 prevents the withdrawal of the tripper, and while in this condition the seal may be applied to the bolt E by inserting the head E' of the latter through the three registered apertures. The tripper being now thrust inward, the neck E² of the bolt passes into the slot or narrow elongation A³ A⁸ in the sheath, and in this movement the tripper-slot C' is brought 30 to the ends of the catches D D, which immediately close up, thrusting their ends through the slot C', and thus securing the tripper with respect to the sheath. After the engagement of the catches with the tripper the latter has a further range of inward movement by virtue of the length of the slot C', which carries 35 the neck of the bolt still farther into the slot A³. The neck E² is preferably only long enough to accommodate the thickness of the three pieces of metal which are thus engaged 40 about it, so that there is no room for manipulating the metal by folding it up or otherwise mutilating the edges of the slots to permit disengagement, or at least so that such manipulation cannot be effected without obviously ruining the device or rupturing the 45 metal beyond concealment.

In the form shown in Figs. 9 and 10 the construction is the same as above described, except that instead of or in addition to providing apertures C² and A¹⁰ and A²⁰ the tripper is made continuous and integral with one leaf A' of the sheath and is looped to bring its ends back between the two leaves, as seen in those figures, the loop A^c being large 55 enough when the tripper is at unlocked position to admit the head of the bolt and small enough when the tripper is thrust into locked position to prevent the escape of the head of the bolt through it. The difference between 60 65 the size of the neck and head of the bolt will necessarily be sufficient to more than cover the enlargement of the loop which is per-

mitted by the length of the slot C'. The purpose of the slot C' will now be explained. Both leaves of the sheath extend entirely 70 through the case and appear beyond it—that is, at the side opposite that at which the loop A^c or the apertures A¹⁰ A²⁰ and C² are formed, and one leaf of the sheath has at its protruding part an aperture A⁴. On said leaf there 75 may be formed in any suitable manner, as by embossing, figures or characters which may be read in connection with a figure or character which is formed on the tripper at a position which causes it to appear through 80 the aperture A⁴ when the tripper is thrust into locked position, (see Fig. 3,) and the tripper has preferably an additional character, which is disclosed through the aperture A⁴ when the tripper is thrust inward the further distance permitted by the length of the slot C', and the figure first disclosed is concealed in the sheath beyond the aperture by this additional movement. The tripper may have also characters which at unlocked position 85 are concealed in the sheath beyond the aperture and which are disclosed beyond the end of the sheath by the locking movement or by the subsequent additional movement of the tripper in the same direction. The purpose of this feature of construction is that the number of the seal, in so far as that number is made up of characters which are placed upon the tripper, (and the entire number may be so placed, the exterior characters on the 90 tripper-sheath being omitted, if desired,) shall be unknown until the seal is locked, and that even when thus locked a portion at least of the characters constituting the serial number or other arbitrary record-mark shall be 95 concealed, so that the record of the seal cannot be taken unless the operator handles it and moves the tripper in the sheath to disclose the concealed figures or characters, the movement required being preferably such as 100 will test the integrity of the device and disclose whether it has been tampered with. Broadly, the expedient of concealing part of the serial number at one position of the movable securing device is covered in my application, Serial No. 658,158, filed November 11, 105 115 1997, and it is not broadly claimed in this case.

The use of a plurality of catches D D D, &c., whether the number be two or more, is 110 to make the seal, as respects the possibility of picking it, substantially a combination-lock, because in order to release the tripper by any manipulation of the catches, if that should be possible through apertures which 115 might be formed in the case and afterward concealed, it would be necessary not simply to bring one of the catches into position where its ends might be spread so as to permit it to be slipped out of the slot C' of the tripper, 120 but to bring all the rings to such position at the same time, and it would be practically impossible, even if one ring could be thus manipulated, to keep it in the right position 125 130

while attempting to manipulate the remainder. I have shown four rings, but evidently the number which may be employed is limited by the space which may be provided in the case.

5 I claim—

1. In a self-locking seal, a catch and a tripper and a case which incloses the catch and in which the tripper is by construction lodged and retained at all unlocked positions; the tripper bearing a character which is concealed within the case at all unlocked positions of the tripper, the movement of the tripper to locked position being such as to

15 disclose such character.

2. In a self-locking seal, a catch and a tripper, and a case which incloses the catch and in which the tripper is by construction lodged and retained at all unlocked positions; the tripper having a range of movement with respect to the case after it is engaged by the catch, and bearing a character which is concealed by the case at all locked positions and disclosed at one limit of said range of movement.

25 3. In a self-locking seal, a catch and a tripper, and a case which incloses the catch and in which the tripper is lodged and retained at all unlocked positions, the tripper bearing 30 a serial number or other arbitrary succession of characters; the case having an aperture through which part of such characters may be disclosed, the unlocked position of the tripper in the case being such as to conceal 35 a part, at least, of the characters, and the locked position being such as to disclose the same through the aperture.

4. In a self-locking seal, a catch and a tripper, and a case which incloses the catch in 40 which the tripper is by construction lodged and retained at all unlocked positions; the tripper bearing a serial number or arbitrary succession of characters, a part of said characters being concealed within the case at all 45 unlocked positions, and disclosed by the movement of the tripper to locked position, the tripper having a range of movement while locked adapted to disclose other of said characters.

5. In a self-locking seal, a catch and a tripper, and a case which incloses the catch, and in which the tripper is by construction lodged and retained at all unlocked positions, the case having an aperture which discloses the 55 tripper, the tripper being adapted to be thrust entirely through the case and to protrude beyond it, and bearing a plurality of characters which are concealed by the case at all unlocked positions of the tripper, the movement 60 of the tripper to locked position being adapted to disclose part of such characters through said aperture, the tripper having a range of movement, while locked, adapted to disclose other characters through said aperture, and 65 to disclose still other characters at its protruding end beyond the case.

6. In a self-locking seal, in combination with the body or case, an elastically-operating catch lodged in the case, adapted to react into locking position; a tripper which is 70 by construction lodged and retained in the case with range of movement relative thereto and which, in position of construction, holds the catch under tension ready to react upon being released, and at another position 75 in such range of movement releases the catch, the latter being adapted when released to react into engagement with the tripper.

7. In a self-locking seal, in combination with the body or case, a tripper which by construction is lodged and retained in the case, an elastically-operating catch lodged within the case and held under tension by the tripper ready to react upon being released, the tripper being stopped against movement in 80 one direction with respect to the case and free to move in the other direction, and being adapted, upon movement in said other direction, to release the catch, and the catch being adapted upon being released to engage the 85 tripper and means whereby such movement of the tripper secures the seal to the object to be protected by it.

8. In a self-locking seal, in combination with the body or case, a plurality of elastically-operating catches lodged unattached therein and inclosed thereby; a tripper which extends within the case and is adapted to be engaged by said catches, and suitable means for holding the catches under tension ready 95 to engage the same when tripped, the tripper having range of movement with respect to the case and adapted in such range of movement to secure the seal to the object to be 100 protected and trip the catches.

9. In a self-locking seal, in combination with the case, the locking element therein, being a plurality of elastically-operating catches each of which is normally a closed coil adapted to be put under tension by being 105 spread open and which are by construction lodged unattached in the case with their ends spread; a spreading element which is movable relatively to the catches to release the latter from tension and permit them to close. 110

10. In a self-locking seal, a catch and a tripper and a case which incloses the catch, the tripper being by construction lodged in the case, one of said parts bearing a character which is concealed by the other at unlocked 115 positions, the movement of the tripper to locked position being such as to disclose such character.

11. In a self-locking seal, a catch and a tripper and a case which incloses the catch, the 120 tripper being by construction lodged in the case, the tripper after it is engaged by the catch having a range of movement with respect to the case, one of said parts bearing a character which is concealed by the other at 125 all locked positions and disclosed at one limit of said range of movement.

12. In a self-locking seal, a catch and a tripper and a case which incloses the catch, the tripper being by construction lodged in the case, one of said parts bearing a serial number or other arbitrary succession of characters, certain of said characters being concealed by the other of said relatively-movable parts at all unlocked positions, and disclosed by the movement of the tripper to locked position, the tripper having a range of movement,

while locked adapted to disclose other of said characters.

In testimony whereof I have hereunto set my hand, in the presence of two witnesses, this 31st day of January, A. D. 1898.

EMIL TYDEN.
